UNITED STATES PATENT OFFICE

JOSEPH R. RICHER, OF OAK PARK, ILLINOIS

HOB GRINDING MACHINE

Application filed June 28, 1930. Serial No. 464,461.

My invention relates to grinding machines and particularly to machines for grinding hob teeth.

Heretofore it has been a common practice to use a conical grinding wheel for grinding the sides of hob teeth. This wheel has been mounted on a spindle which in turn is carried by a holder, and the holder has been shiftable so as to enable the conical wheel to be shifted in accordance with the angle of the thread in the hob. One of the difficulties which has been presented in connection with the conventional machines, resides in the fact that when the grinding wheel is shifted for the purpose of accommodating said wheel to the thread angle, the point of contact of the wheel with the work is shifted, thereby inducing certain errors which must be compensated for.

It is one of the primary objects of the present invention to provide a machine for grinding hobs and the like, in which the line of contact of the grinder with the work will not be shifted when the spindle of the grinder is tilted for the purpose of adjusting the grinder to conform to the angle of the thread in a hob.

Another object is to provide a grinding machine, in which a theoretical, correct axis is provided, about which a grinder head may be tilted in accordance with the helix angle of the thread in a hob for the purpose set forth above.

More specifically, it is an object of my invention to provide a grinding machine with a tilttable grinder holder, the axis of said grinder holder when extended being substantially coincident with the line contact of the grinder with the work.

Still another object is to provide simple and improved means, whereby the reciprocating stroke of a grinder may be varied while the grinding machine is in operation.

A further object is to provide in a machine for grinding hob teeth and the like having a rotary cam for effecting the reciprocation of a grinder, means for preventing rotation of the cam as a result of spring pressure acting against an inclined surface thereon.

A still further object is to provide a machine as set forth above having improved

means for causing the grinding wheel to operate upon the hob teeth as said wheel is being moved away from the axis of the supported hob.

Numerous other objects and advantages will be apparent from the following detailed description when considered in connection with the accompanying drawings, wherein—

Figure 1 is a front elevational view of a grinding machine which is representative of one embodiment of my invention;

Figure 2 is an enlarged vertical sectional view of the machine taken substantially along the line 2—2 of Figure 1;

Figure 3 is a longitudinal vertical sectional view taken substantially along the line 3—3 of Figure 2;

Figure 4 is an enlarged plan view of the grinder head and work support shown in Figure 1, certain portions of the grinder, as well as the supported hob, being shown in section for the purpose of more clearly illustrating my invention;

Figure 5 is a detail vertical sectional view taken substantially along the line 5—5 of Figure 4;

Figure 6 is a plan view similar to Figure 4, disclosing the grinder shifted to a position for grinding the opposite sides of the hob teeth;

Figure 7 is an enlarged sectional view taken along the line 8—8 of Figure 4 to more clearly show the relation between the grinder, the axis about which it is tilttable, and the axis of the work spindle; and

Figure 8 is a vertical transverse sectional view of the work spindle and lead screw, said view being taken substantially along the line 8—8 of Figure 3.

Referring now to the drawings more in detail, wherein like numerals have been employed to designate similar parts throughout the various figures, it will be observed that one embodiment of my invention resides in a hob grinding machine which includes a frame 10, which is supported by a suitable base 12. The upper portion of the frame 10 presents a housing 14 which encloses a work supporting spindle 16. This spindle 16 is provided with a reduced work

supporting end 18 which is adapted to receive and rotate a hob 20. A bearing 22 provides one support for the spindle, while the opposite extremity of the spindle passes through a hollow lead screw 24. This lead screw 24 is supported by and is rotatable within a companion split nut 26 which is secured against rotation within an annular supporting member 28, later to be described.

10 Rotation is imparted to the spindle 16 through the agency of a large gear 30 mounted thereon which meshes with an elongated pinion 32, Figure 3. This pinion 32 is driven from a motor 34 shown in Figure 1. A clutch mechanism 36 is controlled by a manually shiftable lever 38. This clutch 36 may be of any conventional design and when the lever 36 occupies the central position shown in Figure 1, power will not be delivered to the elongated pinion 32. By shifting the lever to one side, rotation will be imparted in a given direction to the pinion, and a reverse direction of rotation will be occasioned when the lever is shifted to the opposite side.

The hollow lead screw 24 may be directly coupled with the spindle 16 by means of a radial arm 40, Figure 3, which is clamped in position upon the outer end of the lead screw 30 and a second arm 42 pivotally carried upon the arm 40 which is adapted to interlock with a gear 44 mounted upon the left extremity of the work spindle. When the pivoted arm 42 is swung downwardly to the position shown in Figure 3 and is interlocked with the teeth of the gear 44, a direct driving connection is established between the hollow lead screw 24 and the work spindle. When it is desired to longitudinally adjust the position of the spindle without disturbing the position of any of the other parts of the machine such as the position of the grinder head 46, later to be described, the arm 42 may be swung out of engagement with the teeth in the gear 44. It will be noted that the hollow lead screw is supported at one extremity upon a tapered bearing surface 48 of the spindle and at its opposite extremity upon the tapered bearing surface 50 of a collar 50 which is continually urged against the companion tapered surface of the lead screw by means of a coiled spring 52 which is interposed between the collar 50 and the gear 44. In this manner the lead screw is supported at both extremities and when the driving connection between the lead screw and the spindle is interrupted as by raising the arm 42, rotation may be imparted to said lead screw by manually turning a hand wheel 54.

Referring now to the grinder head 46 referred to above and particularly to Figures 2, 4, 6, and 7, it will be seen that this grinder head includes a holder 56 for supporting a cylindrical housing 58. This housing 58 in

turn supports a grinding spindle 60 which carries a conical grinding wheel 62. The specific construction of the spindle and its cylindrical support is clearly shown in Figure 4. This grinder spindle 60 is driven at high speed by a motor 64 which is coupled therewith through the agency of a suitable belt 66 and pulley 68. Screws 70 in the holder 56, when tightened, firmly clamp the cylindrical housing 58 in position. This holder 56 is provided with an integral base section 72, Figures 4 to 6 inclusive, which is provided with an aperture 74 for receiving a vertically disposed securing bolt 76. The base section 72 is provided with a central portion having opposed cylindrical surfaces, the lower surface resting against a companion cylindrical surface provided in a support 78, and the upper cylindrical surface adapted to receive a clamping plate 80. This plate 80 is clamped against the cylindrical surface of the section 72 by means of the bolt 76.

If a line coincident with the line of contact at the point of tangency of the grinding wheel 62 and the tooth of the hob 20 is extended, this line will pass through the center of the bolt 76 as clearly shown in Figure 4 wherein said line is designated by the dot and dash line 84. This line 84 crosses the axis of the bolt 76 at a point included within the axis about which the base section is adjustably rotatable. This point is designated by the letter A in Figure 5. In other words, the grinder head 46 is adjustable about an axis which if extended, is coincident with the line of contact or tangency of the grinder wheel 62 and the tooth of the supported hob. Adjustments about this axis are made for the purpose of accommodating the work spindle and its supported grinder wheel to the particular thread angle of the hob. It has been common practice heretofore to adjust a conical grinding wheel about an axis in accordance with the thread angle of a supported hob, but to my knowledge this adjustment has not heretofore been made about an axis which is disposed in the manner shown in the drawings, namely an axis which is parallel to and in fact coincident with the line of contact made between the conical surface of the grinder and the side of the hob tooth.

By having the grinder adjustable about the above mentioned axis, it will be seen that regardless of the position to which the grinder spindle is shifted for the purpose of adjusting the grinder to a particular thread, no variation in the line contact by the grinder wheel will be occasioned. This is to be clearly distinguished from devices which have been used heretofore wherein a grinder head is shifted about an axis which is so positioned as to introduce variation in the vertical disposition of the line contact made

by the grinder wheel when adjustments for thread angle are made. It will also be noticed that this axis which is designated by the line 84, Figure 4, lies in a horizontal plane and intersects the axis of the work supporting spindle 16. Furthermore, this axis or line 84 is positioned obliquely with respect to the axis of the work spindle. In Figure 7 I have designated the axis of the work spindle by a dot and dash line 86, the axis of the grinder wheel by a dot and dash line 88, and a third dot and dash line 90 diagrammatically designates the side surface of the hob teeth or in other words, the thread angle. From the foregoing description it will be apparent that the center line of adjustment of the grinder or, in other words, the axis of tilting thereof is parallel to the grinding zone of the grinder wheel and is contained therein so that when the grinder head is tilted about this line, the contact line within said grinding zone is not disturbed vertically at any part thereof.

The support 78 for the grinder head 46 is mounted upon a suitable plate 91 which is in turn mounted on a slide 92 and is secured to said slide by means of bolts 94 and 96, Figure 2. This slide 92 is adjustable in parallelism with the axis 86 of the work spindle 16 upon a guide frame 98 through the agency of a suitable control handle 100. Figure 1.

This guide frame 98 extends transversely of the machine and is mounted upon suitable anti-friction or ball bearing supports 102 and 35 is transversely shiftable on said support. A coiled spring 104 serves to continually urge the guide frame or slide to the left, Figure 2, the upper extremities of said spring being secured to the rear end of the guide frame and 40 the lower end secured in a fixed position upon the machine frame 10. It will thus be apparent that the guide frame 98 is reciprocable transversely of the machine for the purpose of properly presenting the grinder wheel to 45 the relieved surfaces of the hob teeth. Transverse movement of the slide 98 is controlled by means of a cam 106 which is mounted upon a shaft 108, Figures 2 and 3. This cam rotates in the direction indicated by the arrow 50 in Figure 2 and engages the lower end of an actuating finger 110, which finger is pivotally connected at its upper extremity to the under-side of an adjustable member or frame 112. The left surface of the finger 110, as viewed 55 in Figure 2, fulcrums upon the adjacent edge of a V-shaped projection 114 which is carried by an adjusting screw 116. A depending lug 118 at the lower end of a bolt 120 provides the pivotal support for the finger 110 and the frame 112 which carries the depending lug 118 is adjustable transversely of the machine by means of a suitable handle 122 carried at 60 the outer extremity of a screw 124, Figure 2. In other words, horizontal adjustment of the 65 pivotal point of the finger 110 with respect

to the guide frame 98 may be made by manually manipulating the handle 122. Vertical adjustment of the fulcrum or projection 114 may be made by imparting rotation to the screw 116 and this is occasioned by applying 70 a wrench or similar device to the outer square end of a stub shaft 126 which is connected by bevel gears 128 and 130 to the screw 116. A tightening or lock nut 132 serves to lock the projection or fulcrum 118 75 in its various positions of vertical adjustment. It will be apparent that the vertical adjustment of the fulcrum may be made without interrupting the operation of the cam 106. 80

It will be observed that as the cam 106 moves from the position shown in Figure 2, the finger 110 will be gradually swung in a clockwise direction about the fulcrum 114, thereby imparting a gradual rearward movement to the grinder wheel 62. The cam is so constructed that the shifting of the grinder wheel will be in accordance with the relief in the hob teeth. In this connection it should be observed that it is the usual practice to feed a grinding wheel toward the work in grinding the relieved surfaces of hob teeth and that my invention contemplates the application of the tool or grinder wheel in a reverse direction, namely, in a direction 90 away from the work. When the cam 106 has been rotated so as to bring the flat side surface 106a into engagement with the finger 110, a sudden movement toward the work will be experienced by the grinder wheel so as to 95 carry said wheel into position to grind the next succeeding hob tooth.

Rotation is imparted to the cam shaft 108 by means of a clutch mechanism which I have designated generally by the numeral 134, Figure 3. This mechanism includes a clutch member 136 which is secured to the cam shaft 108 and a member 138 which is resiliently connected to a drive shaft 140 through the agency of a coiled spring 142. This shaft 140 is 100 driven through a train of gears connected with the elongated pinion 32. Certain of these gears are designated in Figure 1 by the numerals 144 and 146. Springs 148 positioned on opposite sides of the guide frame 115 98 serve to hold said frame against its ball bearing support.

Particular attention is directed to the manner in which I have constructed the jaws of the clutch members 136 and 138. It will be 110 apparent that when the clutch members are operatively engaged and the shafts 140 and 108 are rotating in a counter-clockwise direction as viewed in Figures 2 and 3, there will be a positive yielding driving force imparted 125 to the cam shaft 108. However, when the elongated pinion 32 is rotated in a reverse direction for the purpose of shifting the work spindle in a reverse direction, the inclination 130 of the clutch jaws is such as to enable the

clutch member 138 to click past the clutch member 136 so as not to disturb the setting or timing of the grinding wheel.

When the highest surface portion of the cam 106, namely the surface portion designated by the numeral 106b, engages the finger 110, the grinder wheel 62 will be positioned out of engagement with the hob teeth so as to clear the tops of said teeth. In other words, the cam is so designed that when the grinding action of the wheel is completed, said wheel is moved so as to clear the tops of the hob teeth. It will thus be apparent that when a grinding operation from one extremity of the hob tooth to the other has been completed, it is desirable to have the grinding wheel positioned out of engagement with the work in order to facilitate the rearward shifting of the work spindle. In order to insure the positioning of the grinder wheel out of engagement with the work when the machine is thrown in reverse, I employ a pawl 147, Figures 2 and 3, which is adapted to engage a tooth 149 of a ratchet 151 which is rotatable with the cam shaft 108. It will be seen from these figures that when the cam shaft is reversed, that is, when it is rotated in a direction opposite to that indicated in Figure 2, the tooth 149 of the ratchet will engage the pawl 147 when the surface portion 106b of the cam engages the actuating finger 110. After the cam 106 is thus secured against reverse rotation by said pawl and ratchet mechanism, the clutch member 138 will click past the clutch member 136. In this manner the grinder wheel will be automatically positioned out of engagement with the work the instant that the machine is thrown into reverse. This eliminates the usual manual manipulation of the grinder wheel slide by the operator in order to move the grinder wheel away from the work piece. When the grinding machine is thrown into forward or operating movement, the pawl 147 will click past the ratchet 151 and the grinder will perform its usual relieving operation.

Attention is further directed to the fact that I provide engaging surfaces at the point designated by the letter B in Figure 3 which are such as to prevent the cam 106 from being rotated ahead of its normal position when the finger 110 engages the flat surface 106a during the forward rotation of the cam as indicated by the arrow in Figure 2. In other words, the action of the springs 104 upon the finger 110 would be such, when said finger engages the cam surface 106a, as to cause the cam 106 to rotate in a direction indicated by the arrow in Figure 2 if sufficient resistance were not offered by the engaging surfaces at the point B, Figure 3. It might be stated that the clutch members 136 and 138 are locked in both directions while in driving position, but are impossibly locked when

the machine is operated in a reverse direction to bring the work spindle back to its starting position. That is to say, the action of the spring 104 is sufficiently counteracted by the frictional engagement of the clutch jaw at the point B to prevent the finger 110 from rotating and thus destroying the timing of the cam 106 but said surfaces do not offer sufficient resistance to prevent the clutch member 138 from clicking past the clutch member 134 when the grinding machine is thrown in reverse and the ratchet tooth 149 engages the pawl 147.

Attention is now directed to the specific manner in which I mount the hollow lead screw 24 in the split nut 26, see Figures 3 and 8. The nut 26 is provided with oppositely disposed radial lugs 148 and these lugs 148 project upwardly into companion apertures provided within the annular housing 28. This housing 28 is provided in two sections which are secured together by means of suitable screws 150. Springs 152 resiliently urge the split sections of the nut 26 toward the threads in the lead screw, thereby taking up all back-lash or wear. The housing members 28 are pivotally supported and secured within a bearing 154 by means of suitable pins 156. From the foregoing it will be seen that the hollow lead screw is in reality rotatable within a universally supported nut. This will be apparent when it is seen that the lugs 148 provide an axis in one direction for said nut while the pins 156 provide a second axis at right angles to the axis of said lugs. This arrangement provides a very practical and serviceable supporting arrangement. Any variations experienced by the lead screw will be taken up in such a universal support, thereby enabling said lead screw to be subjected to severe usage over an extended period of time without the necessity of replacement.

In Figure 6 I have shown the manner in which the grinder head may be positioned to grind the side of the hob teeth opposite to that shown in Figure 4. This is accomplished by shifting the bolt 76 to an aperture 158, Figure 5, provided in the plate 91. In this new position the base section 72 is inverted and secured in position as shown in Figure 6. The dot and dash line 84a shown in Figure 6 corresponds to the line 84 described above in that said line is coincident with the line contact between the grinder wheel 62 and the side of the hob teeth.

In the drawings I have disclosed a truing mechanism which is indicated generally by the numeral 160. This truing mechanism per se does not form the subject matter of my present invention but is merely shown in combination with the grinder head 46. This truing mechanism includes a block or frame 162 which is dovetailed to one extremity of the base section 72 as clearly shown in Fig-

ure 7. A finger 164 is positioned adjacent the conical side of the grinding wheel and is adapted to be moved across the surface thereof for the purpose of truing said wheel.

5 From the foregoing description it will be apparent that my invention contemplates the provision of improved means and methods whereby the sides of a hob tooth may be ground. By tilting the grinder about an axis 10 which, if extended, is coincident with and parallel to the line contact between the grinder and the work, errors which have heretofore been introduced as a result of the shifting of this line contact, are avoided.

15 My improved apparatus is of simple design and may be manufactured by the practice of usual machine shop methods. Shifting the grinder wheel away from the axis of the work piece in the manner set forth above, 20 has proven very satisfactory and my improved means for shifting the position of the fulcrum which bears against the actuating finger enables adjustments to be made while the machine is in operation. The improved 25 "click clutch" arrangement in combination with the type of cam surface shown in the drawings, precludes the possibility of rotating the cam ahead of its timed position. By practicing my improved method, hobs 30 may be ground in a very expeditious and economical manner.

It will also be apparent that my grinder may be moved toward the work piece during the grinding operation instead of away from the work, as above described, by merely positioning the contact lever or finger 110 on the opposite side of the cam. By positioning the parts in this manner the grinder will be moved slightly toward the work and rapidly 40 away from the work.

Changes in the specific arrangement of the structure shown in the drawings may be made without departing from the spirit and scope of my invention, and said invention 45 should be limited only by the scope of the appended claims.

Having thus described my invention, what I claim as new and desire to secure by Letters Patent is:

50 1. In a hob grinding machine, a rotatable work support, a grinder spindle, a grinder on said spindle, a holder for said spindle, means for tiltably supporting said holder, the axis about which said holder is tiltable, 55 if projected, being substantially coincident with the line of contact of the grinder with the work, and means for imparting relative movement between the grinder and the work in accordance with the relief on the hob 60 teeth.

2. In a hob grinding machine, a rotatable work support, a grinder spindle, a grinder on said spindle, a holder for said spindle, means for tiltably supporting said holder, 65 the axis about which said holder is tiltable, if

extended, being substantially coincident with the line of contact of the grinder with the work and inclined with respect to and intersecting the axis of the rotatable work support, and means for imparting relative movement between the grinder and the work in accordance with the relief on the hob teeth. 70

3. In a hob grinding machine, a rotatable work support, a grinder spindle, a conical grinder on said spindle, a holder for said spindle, means for tiltably supporting said holder, the axis about which said holder is tiltable, if projected, being substantially coincident with the line of contact of the conical surface of the grinder with the work 75 whereby to enable the shifting of said grinder in accordance with the thread angle of the hob without disturbing the line contact of the grinder with the work, and means for imparting relative movement between the grinder and the work in accordance with the relief on the hob teeth. 80

4. In a hob grinding machine, a rotatable work support, a grinder spindle, a grinder on said spindle, a holder for said spindle, 90 means for tiltably supporting said holder, said holder being tiltable about an axis positioned obliquely with respect to the axis of the rotatable work support and shiftable about an axis at substantially right angles 95 with respect to the axis of said rotatable work support, and means for imparting relative movement between the grinder and the work in accordance with the relief on the hob teeth. 100

5. In a hob grinding machine, a rotatable work support, a grinder spindle having its axis of rotation substantially normal to the hob helix, a grinder on said spindle, a holder for said spindle, means for tiltably supporting said holder, the axis about which said holder is tiltable, if projected, being substantially coincident with the line of contact of the grinder with the work, and means for 105 imparting relative movement between the grinder and the work in accordance with the relief on the hob teeth. 110

6. In a hob grinding machine, a rotatable work support, a grinder spindle, a grinder on said spindle, a holder for said spindle, and 115 means for tiltably supporting said holder, said holder being tiltable about a substantially horizontal axis which is oblique with respect to the axis of the work support for adjusting said grinder to the thread angle of 120 the hob and shiftable about a substantially vertical axis for adjusting to the pressure angle of the hob.

7. In a hob grinding machine, a rotatable work support, a grinder spindle, a grinder on 125 said spindle, a holder for said spindle, means for tiltably supporting said holder, and means for imparting relative reciprocation between the grinder and supported work, said holder being tiltable about an axis 130

oblique to the axis of the work support for adjusting said grinder to the thread angle of the hob and shiftable about an axis, substantially normal to the plane of reciprocation for adjusting said grinder to the pressure angle of the hob.

8. In a hob grinding machine, a rotatable work support, a grinder spindle, a grinder carried by said spindle, a holder for said spindle, said holder having an outer cylindrical bearing surface, a support having a companion cylindrical surface for receiving the cylindrical surface of said holder, means for imparting relative reciprocation between the grinder and the work, and a pivot for said holder having an axis substantially normal to the plane of reciprocation.

9. In a hob grinding machine, a rotatable work support, a grinder, means for imparting relative reciprocation between the grinder and the work in accordance with the relief in the hob teeth, a lead screw for imparting longitudinal movement to said work support, a nut in which the lead screw is movable, and means for supporting said nut about a pair of axes disposed at substantially right angles to each other, whereby to present a universal support for said nut.

10. In a hob grinding machine, a rotatable work support, a grinder, means for imparting relative reciprocation between the grinder and the work in accordance with the relief in the hob teeth, a lead screw for imparting longitudinal movement to said work support, a nut in which the lead screw is movable, an annular means providing a pivotal support for said nut, and a bearing providing a pivotal support for said annular means.

11. In a hob grinding machine, a rotatable work support, a grinder, means for imparting relative reciprocation between the grinder and the work in accordance with the relief in the hob teeth, a lead screw for imparting longitudinal movement to said work support, a split nut in which the lead screw is movable, means for supporting said split nut about a pair of axes so as to present a universal support, and resilient means for continuously urging the split portions of the nut against the lead screw.

12. In a machine of the class described, a rotatable support, means for imparting longitudinal movement to said support including a lead screw, a split nut for said lead screw, resilient means for continuously urging said nut toward said lead screw, means for supporting said nut about a transverse axis, and means for supporting said nut support about an axis disposed at substantially right angles to said first mentioned axis whereby to present a universal support for said nut.

13. In a machine of the class described, a rotatable work support, a tool for engaging work on said support, a lead screw for impart-

ing longitudinal movement to said work support, driving means for rotating said lead screw, a cam mechanism for imparting relative reciprocation between the tool and work support, said mechanism including a cam having a gradually rising surface and a relatively steep surface, and a clutch mechanism for connecting the driving means with said cam, said clutch mechanism including a pair of clutch jaws adapted to positively connect the parts in one direction of rotation and to impositively connect the parts in the opposite direction of rotation, and an actuating member engaging the cam surface, the impositive frictional engagement of the clutch jaws being greater than the frictional engagement of said actuating member with the steep surface of said cam.

14. In a machine of the class described, a rotatable work support, a tool for engaging work on said support, a lead screw for imparting longitudinal movement to said work support, driving means for rotating said lead screw, a cam mechanism for imparting relative reciprocation between the tool and work support, said mechanism including a cam having a gradually rising surface and a relatively steep surface, and a clutch mechanism for connecting the driving means with said cam, said clutch mechanism including a pair of clutch jaws adapted to positively connect the parts in one direction of rotation and to impositively connect the parts in the opposite direction of rotation, an actuating member engaging the surface of said cam, and a pawl and ratchet mechanism for preventing reverse rotation of said cam and for stopping the cam when the highest surface thereof engages the actuating member.

15. In a machine of the class described, a rotatable work support, a tool for engaging work on said support, a lead screw for imparting longitudinal movement to said work support, driving means for rotating said lead screw, a cam mechanism for imparting relative reciprocation between the tool and work support, said mechanism including a cam having a gradually rising surface and a relatively steep surface, and a clutch mechanism for connecting the driving means with said cam, said clutch mechanism including a pair of clutch jaws adapted to positively connect the parts in one direction of rotation and to impositively connect the parts in the opposite direction of rotation, an actuating member engaging the surface of said cam, a fixed fulcrum about which said actuating member operates, and means for shifting the position of said fixed fulcrum to vary the degree of movement of said actuating member.

16. In a machine of the class described, a rotatable work support, a tool for engaging work on said support, a lead screw for imparting longitudinal movement to said work support, driving means for rotating said lead

5 screw, a cam mechanism for imparting relative reciprocation between the tool and work support, said mechanism including a cam having a gradually rising surface and a relatively steep surface, and a clutch mechanism for connecting the driving means with said cam, said clutch mechanism including a pair of clutch jaws adapted to positively connect the parts in one direction of rotation and to 10 impositively connect the parts in the opposite direction of rotation, an actuating member engaging the surface of said cam, a tool supporting slide pivoted to said actuating member, a fulcrum interposed between said pivotal point and the point of engagement of the member with the cam, and means for adjusting the position of said fulcrum.

15 17. In a hob grinding machine, a rotatable work support, a grinder spindle, a grinder carried by said spindle, a holder for said spindle, a cylindrical bearing for tiltably supporting said holder, and a pivotal device extending through and at substantially right angles to the cylindrical bearing whereby to 20 effect the adjustment of the grinder wheel to the pressure angle of the hob to be ground.

25 18. In a hob grinding machine, a rotatable work support, a grinder spindle, a grinder carried by said spindle, a holder for said spindle, a cylindrical bearing for tiltably supporting said holder, and a clamping mechanism including a clamping screw extending at substantially right angles to and through the cylindrical holder support whereby to 30 effect the adjustment of the grinder in accordance with the required pressure angle of the hob to be ground and to secure said holder in such position.

35 19. In a hob grinding machine, a rotatable hob support, a grinder spindle, a grinder carried by said spindle, a holder for supporting said spindle at either side of a vertical plane that is perpendicular to the hob axis with the spindle substantially perpendicular to the hob 40 helix and oblique to the hob axis, said holder providing a pivotal support to render said spindle adjustable to the thread angle of the hob, the axis of said pivotal support being substantially parallel with the grinding surface of said grinder, means for producing 45 relative travel between the grinder and the hob in a direction parallel to the hob axis, and means for effecting relative transverse movement between the grinder and the hob for 50 grinding the relief on the teeth of the hob.

55 20. In a hob grinding machine, a rotatable hob support, a grinder spindle, a grinder carried by said spindle, a holder for supporting said spindle at either side of a vertical plane 60 that is perpendicular to the hob axis with the spindle substantially perpendicular to the hob helix and oblique to the hob axis, said holder providing a pivotal support to render said spindle adjustable to the thread angle 65 of the hob, the axis of said pivotal support

being substantially parallel with the grinding surface of said grinder, a second pivotal means for rendering the spindle adjustable to the pressure angle of the hob teeth, means for producing relative travel between the grinder and the hob in a direction parallel to the hob axis, and means for effecting relative transverse movement between the grinder and the hob for grinding the relief on the teeth of the hob.

70 21. In a hob grinding machine, a rotatable hob support, a grinder spindle, a grinder carried by said spindle, supporting means for positioning the axis of the grinder spindle substantially perpendicular to the thread helix of the hob and providing a pivotal support for rendering the grinder adjustable to the thread angle of the hob, the axis of said pivotal support being oblique with respect to the axis of the rotatable hob support and substantially parallel with the grinding surface of said grinder, means for effecting relative movement between the grinder and hob support in a direction substantially parallel to the hob support axis, and means for effecting relative transverse movement between the hob support and grinder in accordance with the required relief on the hob teeth.

75 22. In a hob grinding machine, a rotatable work support, a grinder spindle, a grinder on said spindle, a holder for said spindle, means for tiltably supporting said holder, the axis about which said holder is tiltable, if projected, being substantially parallel with the line of contact of the grinder with the work, and means for imparting relative movement between the grinder and the work in accordance with the relief on the hob teeth.

80 23. In a hob grinding machine, a rotatable work support, a grinder spindle, a conical grinder on said spindle, a holder for said spindle, means for tiltably supporting said holder, the axis about which said holder is tiltable, if projected, being substantially parallel with the conical surface of the grinder, and means for imparting relative movement between the grinder and the work in accordance with the relief on the hob teeth.

85 24. In witness whereof, I have hereunto subscribed my name.

90 JOSEPH R. RICHER.
